US00D544347S

(12) **United States Design Patent** (10) **Patent No.:** **US D544,347 S**
Last (45) **Date of Patent:** **** Jun. 12, 2007**

(54) **CAP/CLOSURE**

(75) Inventor: **Laurens Last**, Monaco (MC)

(73) Assignee: **IPN IB B.V.**, Houten (NL)

(**) Term: **14 Years**

(21) Appl. No.: **29/224,496**

(22) Filed: **Mar. 2, 2005**

(30) **Foreign Application Priority Data**

Sep. 3, 2004 (EM) 000222104

(51) **LOC (8) Cl.** **09-07**

(52) **U.S. Cl.** **D9/436; D9/443; D9/444**

(58) **Field of Classification Search** D9/434,

D9/435, 441, 443, 444, 452, 613, 645, 451,

D9/445, 433; 215/355-364, 305, 296, 295,

215/252; D7/710, 659, 656, 651, 628, 619.2,

D7/613, 606, 604, 595, 594, 393, 301

See application file for complete search history.
